UNITED STATES PATENT OFFICE.

RAMON CAMELL, OF RHONE, AND LAURENT COCHET AND JOSEPH GRITTE, OF LYON, FRANCE, ASSIGNORS TO SOCIETE LYONNAISE DES RÉCHAUDS CATALYTIQUES CAMELL, COCHET, GRITTE & CIE. (SOCIÉTÉ EN COMMANDITE), OF CALURE, RHONE, FRANCE.

CATALYTIC HEATING APPARATUS.

1,354,090.

Specification of Letters Patent. Patented Sept. 28, 1920.

Application filed June 13, 1919. Serial No. 304,039.

To all whom it may concern:

Be it known that we, RAMON CAMELL, a citizen of the French Republic, LAURENT COCHET, a citizen of the French Republic, and JOSEPH GRITTE, a subject of the King of Belgium, of St. Rambert l'Ile Barbe, Rhone, France, 93 Boulevard des Belges, Lyon, France, and 93 Rue de la Pyramid, Lyon, France, respectively, have invented certain new and useful Improvements in Catalytic Heating Apparatus, of which the following is a specification.

This invention relates to catalytic heating apparatus requiring preliminary heating of the catalytic mass to start its action, and the purpose of the invention is to provide simple and efficient means for such preliminary heating.

To this end we place in or on the said mass a pellet of spongy platinum, and provide means for introducing a fluid combustible to this pellet, whereby the temperature of the latter is rapidly raised, and the heat radiated by the pellet to the adjacent or surrounding catalytic mass quickly raises this mass to the temperature required for the normal working of the apparatus. The fuel used for the purpose described may be a liquid, vapor or gas, for example liquid or vaporized alcohol or hydrocarbon, or illuminating gas, pure or mixed with air, and the same may be introduced by pressure, suction, capillarity or other convenient means.

The invention is illustrated in the accompanying drawing, which is a vertical section of a catalytic heater provided with one form of the improved preliminary heating device.

In the drawing *a* designates the pellet of spongy platinum, *c* a layer of catalytic ma-

terial, *d* the receptacle containing the latter, and *b* a boss formed in the cover of this receptacle or container, the pellet being placed under this boss, which allows easy access of air to the pellet. Below the container *d* there is a chamber *e* in the form of an inverted truncated cone. At the bottom of this chamber *e* is placed a layer of cotton or other absorbent material *f*, and a tube *g* having a screw stopper *h* enables alcohol or the like to be poured into the chamber *e*, to saturate the absorbent material *f*. An asbestos wick *i* on a rigid holder *j* extends from the absorbent material *f* to the pellet *a*, and carries the alcohol or the like to the pellet. The vapor of the alcohol carried upward in this way impinges on the pellet *a*, and quickly raises the latter to temperature which heats the surrounding catalytic mass *c*, as required for starting the heater.

What we claim as our invention and desire to secure by Letters Patent of the United States is:—

In catalytic heating apparatus, the combination of a container for a catalytic mass, a pellet of spongy platinum in this container, a chamber below said container, means for introducing liquid fuel into said chamber, and means for supporting a wick extending from the interior of said chamber to the pellet in said container.

In witness whereof we have signed this specification in the presence of two witnesses.

RAMON CAMELL.
LAURENT COCHET.
JOSEPH GRITTE.
